UNITED STATES PATENT OFFICE.

JOHN BARNET, OF LAFAYETTE, INDIANA.

MACHINE FOR MILLING OFF THE HUB ENDS OF WHEEL-SPOKES.

SPECIFICATION forming part of Letters Patent No. 293,934, dated February 19, 1884.

Application filed June 4, 1883. (No model.)

To all whom it may concern:

Be it known that I, JOHN BARNET, of Lafayette, in the county of Tippecanoe and State of Indiana, have invented certain new and 5 useful Improvements in Center-Drilling Machines; and I do hereby declare that the following is a full, clear, and exact description thereof, reference being had to the accompanying drawings, and to the letters of reference 10 marked thereon, which form part of this specification, in which—

Figure 1 is a top view of the machine, part of the upper portion of which is broken away, showing the rim of a wheel and two spokes thereof 15 of adjusted in position. Fig. 2 is a vertical section through the machine, taken in the plane indicated by dotted line $x-x$ on Fig. 1. Fig. 3 is a sectional view of the loaded hand-lever and the upper part of the machine.

20 This invention relates to machinery for centering metal wheels having spokes fixed in their rims, but without hubs, and cutting off the inner ends of the spokes true, so that when the hubs are applied the wheel will be round and 25 true; and it consists in certain novel devices for centering the rims of wheels and trimming the inner ends of the spokes, which will be fully understood from the following description, when taken in connection with the annexed 30 drawings.

A designates the solid bed-plate of the machine, from which rise columns B, supporting on their upper ends a horizontal top plate, C. These parts are rigidly secured together, and 35 constitute a substantial supporting-frame. From the center of the bed-plate A, and rigidly secured to it, rises a pillar, D, on top of which is a flange, E, on which is secured the chucking-table or face-plate F, and also the lever-ring G, which latter is to a limited extent 40 circularly movable. The chuck is composed of the said face-plate F, having a suitable number of slots, H, through it, in which work the extensions of movable slides I, and on which 45 are fastened, with set-screws, at equal distances from the center of the machine, angle-jaws J, the slides I of which are connected to a lever-ring, G, under the table F, by means of links K. To the lever-ring G is fastened an arm, L, which 50 is connected to a hand-lever, M, by means of a link, N, said lever being held at any point by a set-screw, O', passed through a slotted arc, O.

On the under side of the top plate, C, is bolted a sleeve, P, having a screw-thread on its outer surface, on which turns the nut-hub of a hand-wheel, Q. On the lower end of the sleeve P a pressure-foot, R, is fitted, having a flange, r, at its lower end, the upper end being hung to the hub of the hand-wheel Q, so that when this wheel is revolved the pressure-foot can be 55 moved either up or down. There is an inner sleeve, S, (with a collar,) resting on top of plate C and passing through the outer sleeve, P, and on the upper end of this inner sleeve is keyed a bevel spur-wheel, T, which engages with and is driven by a pinion, U, on a shaft, U', having its bearings on top of the plate C, as 60 shown in Fig. 2. The sleeve S is bored out to receive a vertically-movable spindle, V, which is slotted to receive a feather or key, and on 65 this rod a loose collar with trunnions W W is held in place by means of slip-collars X X. On the trunnions W W is the yoke Y, to which is attached the balanced lever Z, connected by a link, a, to the plate C. The vertically-movable 70 spindle V is bored out at its lower end to receive suitable drills, reamers, or other tools. On the table F is fastened a center bed or chuck, b, for supporting the inner ends of the spokes, 75 as shown in Fig. 2.

Operation: A tire with spokes fastened in it is adjusted in the machine by resting the tire on the chuck-jaws J, the inner ends of the spokes or arms resting on the center bed, b. The spokes are then clamped fast on said bed by screwing 80 down the pressure-foot R, after which the tire or rim of the wheel is strained outward by applying power to the lever M. It has been above described that the slides I, having the angle-jaws J, are connected by links K to the lever-ring G. 85 This ring G is circularly movable by vibrating the arm L, and the slides are radially adjusted by reason of the links assuming angles with respect to the length of their respective slides; or, in other words, the inner ends of the said 90 links move with the ring G. The spindle V, with a suitable tool attached to it, is then brought down by hand-lever Z, cutting off the inner ends of the spokes to equal lengths, so that when the hub or center is applied the 95 wheel will be round and perfectly true.

Having described my invention, what I claim as new, and desire to secure by Letters Patent, is—

1. In a machine for truing wheels before applying the hubs, the combination of a concentric series of radial tire-distending chucks, a center-block and spoke-clamp, and a drill cutter or reamer adapted for trimming the inner ends of spokes, all constructed and adapted to operate substantially in the manner and for the purposes described.
2. The combination of expanding chucks, a circularly-movable slotted ring, its lever-connections, and the links K, for adjusting said chuck, the central spoke-rest, the spoke-clamps, and a vertically-movable rotary spindle bearing a spoke-cutting tool, all constructed and adapted to operate substantially in the manner and for the purposes described.
3. In combination with the tire-distending chucks, the spoke-clamp, the spindle V, its balanced lever Z, for giving vertical movement to the spindle, the sleeve S, and the driving-wheels for rotating the spindle, all constructed and adapted to operate substantially in the manner and for the purposes described.
4. The combination of the face-plate, the central spoke-rest, the perforated slides T, and the adjustable chuck-jaws on said slides, all constructed and adapted to operate substantially in the manner and for the purposes described.

In testimony that I claim the foregoing as my own I affix my signature in presence of two witnesses.

JOHN BARNET.
